UNITED STATES PATENT OFFICE.

THEODORE SAUNDERS, OF DANBURY, CONNECTICUT, ASSIGNOR OF ONE-HALF TO FREDERICK A. HULL, OF SAME PLACE.

CAR HEATER AND VENTILATOR.

SPECIFICATION forming part of Letters Patent No. 372,989, dated November 8, 1887.

Application filed June 4, 1887. Serial No. 240,282. (No model.)

To all whom it may concern:

Be it known that I, THEODORE SAUNDERS, a citizen of the United States, residing at Danbury, in the county of Fairfield and State of Connecticut, have invented new and useful Improvements in Car Heaters and Ventilators, of which the following is a specification.

This invention relates to improvements in car heaters and ventilators, as set forth in the following specification and claims and illustrated in the accompanying drawings, in which—

Figure 1 is a side elevation of a locomotive with my invention applied, parts being broken away. Fig. 2 is a detail enlarged view, partly in section, of a conducting-tube and adjacent parts.

Similar letters indicate corresponding parts.

In the drawings, the letter A designates a conducting-tube. Said tube is provided with a funnel-shaped inlet, B, and a flexible connection, C, can connect the outlet of the conducting-tube to another tube or series of tubes, D.

E is a trap which is applied to the conducting-tube near its inlet. An escape, F, is secured to said trap. To the conducting-tube are secured the opposite extremities of a coiled heating-tube, G, situated in the boiler-space or other place where it will be heated. Switching-valves H I are applied, respectively, to the conducting-tube and at forward end of the heating-tube, as seen in the drawings. To the conducting-tube A are secured the ends of a branch tube, K, having a valve, L. In the conducting-tube A is a partition, R, located between the ends of the branch tube and dividing said tube A into two sections, one of which communicates with the valve N and the other with the valved inlet O of the pump M. When the locomotive is moving forward, air will enter the inlet B. In case rain or water should enter the inlet, said water will enter the trap E and pass out through the escape F. Said escape is made of such small diameter that little air can escape through it, but large enough to allow the trap E to be cleared of moisture. In case the air entering the conducting-tube is to be used for heating, then

the valve H is closed and the valve I is opened. Said air will then pass from the inlet into the

heating-tube G, where it is warmed, and thence back into the conducting-tube. If the air entering through the inlet B is not to be warmed, the valve I is closed and the valve H is opened. 55 The air will then pass along the tube A without entering the heating-tube G. Supposing the pump M to be at rest and the valve L to be open, then the air passing along the conducting-tube will pass through the branch 60 K, thence back to the tube A, as indicated by arrows, and through the connection C and tube D, from whence the air can be led into cars to ventilate and heat the same. In warm weather the air will of course not be heated, 65 and will then serve to cool the car. In case the locomotive is not moving forward air can still be forced through the conducting-tube. To accomplish this result the valve L is closed and the pump M is set in operation. The action of the pump will draw in the air through the valved inlet N and expel said air through the valved inlet O. As said valves are properly connected with the sections of the tube A, as seen, said action of the pump will 70 cause air to flow through said tube A, as indicated by arrows in Fig. 2. The valve L is suitably connected to a lever, P, in the cab S, so as to be in reach of the driver or operator. The lever Q in the cab S connects with a valve 75 through which steam can be admitted to the pump to set said pump in operation. The heating-tube and conducting-tube can be connected by suitable means—such as flanges and bolts—so that said tubes can be disconnected, 80 when desired, for such purposes as cleaning or repairing. The air from the conducting-tube can be utilized to heat or to cool a car by either passing or blowing said air into a car or through a radiator or other device in such 85 car. It should also be noticed that the heating-tube G, which is shown in the form of a coil, can be made of any other suitable form that may be desirable.

What I claim as new, and desire to secure 95 by Letters Patent, is—

1. The combination of the conducting-tube having a trap provided with a water-escape orifice, a heating-tube communicating at its extremities with the conducting-tube, and two 100 switching-valves arranged, respectively, at the forward extremity of the heating-tube and

in the conducting-tube between the attached extremities of the heating-tube, substantially as and for the purposes described.

2. The combination of the conducting-tube, 5 the heating-tube having its extremities communicating with the conducting-tube, two switching-valves arranged, respectively, at the forward extremity of the heating-tube and in the conducting-tube between the extremities of the heating-tube, a branch tube having its ends connected with the conducting-tube and provided with a valve, a partition in the conducting-tube between the ends of the branch tube, and a pump having a 15 valved inlet and a valved outlet communicating, respectively, with the conducting-tube at opposite sides of the partition, substantially as described.

3. The combination of a conducting-tube, a

heating-tube having its extremities communicating with the conducting-tube, two switching-valves arranged, respectively, at the forward extremity of the heating-tube and in the conducting-tube between two extremities of the heating-tube, a partition in the conducting-tube, and a pump having a valved inlet and a valved outlet connected, respectively, with the conducting-tube at opposite 25 sides of the partition, substantially as described.

In testimony whereof I have hereunto set my hand and seal in the presence of two subscribing witnesses.

THEO. SAUNDERS. [L. S.]
